Des. 177,625
Patented May 8, 1956

177,625

CHILD'S HANDBAG

Sidney Hyman, New York, N. Y.

Application December 16, 1955, Serial No. 39,358

Term of patent 3½ years

(Cl. D87—3)

Fig. 1 is a front perspective view of a child's handbag, showing my new design;

Fig. 2 is a similar view thereof, with the cover opened; and

Fig. 3 is a rear elevational view thereof.

I claim:

The ornamental design for a child's handbag, as shown.
